ATTORNEY.

UNITED STATES PATENT OFFICE.

THOMAS THEODORE HART, OF BRADFORD, PENNSYLVANIA.

COASTING-SLED.

1,245,227.

Specification of Letters Patent.

Patented Nov. 6, 1917.

Application filed July 17, 1917. Serial No. 181,013.

To all whom it may concern:

Be it known that I, THOMAS T. HART, a citizen of the United States, residing at Bradford, in the county of McKean and 5 State of Pennsylvania, have invented certain new and useful Improvements in Coasting-Sleds; and I do hereby declare the following to be a full, clear, and exact description of the invention, such as will enable others skilled in the art to which it 10 pertains to make and use the same.

My invention consists in the novel features hereinafter described, reference being had to the accompanying drawing which 15 illustrates one embodiment of my invention selected by me for purposes of illustration, and the said invention is fully disclosed in the following description and claims.

Referring to the drawings:

20 Figure 1 represents a side elevation of a coasting sled embodying my invention.

Fig. 2 is a front elevation of the same.

Fig. 3 is a vertical sectional view somewhat enlarged of portions of the seat post 25 and the braces associated therewith, and illustrating the manner in which they are connected together.

Fig. 4 is a horizontal sectional view of Fig. 3 at the line 4—4 thereof.

30 Fig. 5 is an enlarged detail view partly in section showing the lower end of one of the lateral braces and its connection with the clamping bolt.

Fig. 6 is an enlarged detail view representing the upper end of one of the lateral brace bars and illustrating a modified form thereof.

Fig. 7 is a section on line 7—7 of Fig. 1.

My invention relates to coasting sleds provided with a single runner, and being of the type commonly known as "jumpers". In the embodiment of my invention herein illustrated, and selected by me for purposes of illustration, 1 represents a runner which 45 is composed preferably of channel iron having a central body portion and upturned lateral flanges. This runner is of considerable length and at each end the flanges are cut away to permit the central body portion being bent upwardly and over upon itself to form rounded portions or eyes indicated at 2. The rear portion of the runner, for example, the portion from x—y Fig. 1 and constituting approximately eleven-thirtieths 50 of the entire length of the runner, is perfectly straight on the bottom. From the

point y forward for a substantially equal distance, as from y—z, Fig. 1, the bottom of the runner curves upwardly a distance approximately equal to one-twenty-fourth of the length of the runner, above a straight line continuous with the bottom of the portion x—y. The remaining forward portion of the runner, from z to w, Fig. 1, and being approximately eight-thirtieths of the length 60 of the runner rises approximately four-thirtieths of the length of the runner above a straight line continuing from the bottom of the portion x—y. I find that this construction of runner assures gradual or easy ascent of 65 snow or other obstruction, and packs the snow very gradually as the runner moves over it so that the straight or flat portion x—y which forms the main bearing surface slides more easily than would otherwise be 70 the case.

The runner is provided with a seat which is supported directly above the straight or flat portion x—y. I prefer to form a seat supporting post, which is also preferably 75 formed of channel iron and which comprises two vertically disposed portions 3 and 4 formed of channel iron and which comprises two vertically disposed portions 3 and 4 bent toward each other to form contacting knees as at 5 and 6, the upper ends of the bars 3 and 4 being connected by a longitudinally disposed portion, 7, which inclines slightly downward from front to rear. I prefer to form this seat post from a single piece of channel iron as shown herein; the lateral flanges of the channel iron being cut 80 away at each end of the horizontal portion 7 to permit the body portion to be bent as shown, the lateral flanges of the channel iron being disposed as shown and the flanges of the part 7 extending upwardly as indicated 85 at 7^a. The lower ends of the bars 3 and 4 of the seat post have their body portions bent horizontally as indicated at 3^a and 4^a and these portions are secured to the runner by bolts and nuts, or by rivets, or by brazing or welding or in any other desired manner.

In order to stiffen the seat post I prefer to provide a front brace, indicated at 8, extending from the forward portion of the runner to the point where the knees 5 and 6 of the seat post come together. For convenience I prefer to make the seat post of channel iron slightly narrower than that used for the runner and I also prefer to 100 make the front brace, 8, of channel iron slightly narrower than that used for the

seat post, so that the upper end of the brace, 8, may lie between the lateral flanges of the portion 4 of the seat post as shown, the said upper end having a portion indicated at 9 in Fig. 3 which lies against the body portion of the part 4 of the seat post. I prefer to provide means for uniting the parts 3 and 4 of the seat post to each other and also to the upper end of the main brace and for this purpose I prefer to employ a clamp comprising a pair of clamping members and a pair of clamping bolts for connecting them. To this end I have shown a clamping member 10 which has an angular portion adapted to engage the exterior face of the knee portion 5 of the post bar 3 and extend a distance above and below the same, the seat clamping member being provided at each side with an eye 11 (see Figs. 1 and 4). I also provide a second clamping member 12 which is constructed to engage an exterior portion of the post bar 4 adjacent to the knee, 6, and extend above the same and also extend over the upturned or bent portion, 9, of the front brace, and for a distance downward therefrom on the body portion of the front brace as clearly shown in Fig. 3. This clamping member is also provided with an eye, 13, on each side. The clamping members may be formed of cast metal or drop forgings as preferred.

The clamping members, 10 and 12, are connected by bolts, 14, which unite them and clamp them upon the knee portions of the seat post and the upper end of the front brace, 8, thus uniting all these parts rigidly. The lower end of the front brace is provided with a horizontally disposed portion, 8^a, which is united to the runner by bolts or rivets or by welding or brazing as may be preferred. I prefer to extend the foot portion, 8^a, of the brace 8 along the upper face of the main body of the runner a considerable distance and preferably to the forward end of the runner, as shown in the drawing in Figs. 1 and 7, so that the foot portion, 8^a, reinforces the forward end of the runner in front of the brace 8 and stiffens it so as to prevent the runner from being bent upwardly in case it strikes a stone or other obstruction.

15 represents a seat which is disposed transversely with respect to the runner and is provided on its under side, centrally, with a pair of kerfs, 16, or grooves to engage the lateral flanges 7^a of the top piece, 7, of the seat post, as clearly shown in Fig. 2, thus affording a firm support for the seat and preventing the seat from moving laterally or twisting with respect to the seat post. I may also provide the seat with outwardly extending pins, 17, adapted to pass through holes in the body portion of the top piece, 7, of the seat post to prevent the seat from moving longitudinally with respect thereto.

In order to firmly unite the seat to the post and brace it, I prefer to provide lateral braces indicated at 18 which are also preferably made of channel iron, the lower ends having the lateral flanges cut away and the main body bent or curved as indicated at 19, Fig. 5, to embrace one of the bolts, 14, and the upper end of each brace bar 18 is connected to the seat. In Figs. 1 and 2 I have shown the upper ends of the braces, 18, perforated and secured to screw eyes, 20, which are screwed in to the under side of the seat and in this construction the screw eyes are screwed into the seat before the lower ends of the braces are connected with the bolts 14. The braces, 18, as will be seen, unite the seat firmly to the seat post and prevent any rocking of the seat with respect to the post.

I may in some instances connect the upper ends of the braces, 18, detachably to the seat. For example, in Fig. 6, I have shown a modified form of brace bar indicated at 18^a, the upper end of which is provided with a horizontal portion 18^b having therein a slot 18^c extending transversely and of such length as to permit the passage of a screw eye therethrough, the screw eye being indicated at 21^a. Where this construction is used, the screw eyes can be inserted in the bottom of the seat at the proper point and the brace bars 18^a may be connected by simply slipping the slot 18^c over the head of the screw eye and turning the screw eye at right angles to the slot, and in like manner by turning these screw eyes the brace bars may be disconnected and the seat lifted off, the lateral braces falling to a vertical position on each side of the seat post, swinging on the bolts 14 hinge fashion, and this will be found very convenient for packing or storing the device. In the construction shown in Figs. 1 to 5 the seat may be detached by disconnecting the bolts 14 and nuts 14^a and removing the bolts, leaving the lateral braces connected with the seat.

In packing the devices for shipment or for storing them in the house when not in use, the seat will be disconnected and laid flat against the seat post. In packing a quantity of these devices for shipment the eyes or loops 2, 2 at the ends of the runner perform an additional function in that they may be slipped over a pair of rods which will connect any desired number of the devices in very compact and convenient form for shipment.

The seat 15 is also preferably provided at each end with hand holds which may be recesses, 21, as shown in Fig. 2, cut in the under face of the seat or the seat may be provided with hand holds in any other desired manner.

As will be obvious in using this device in coasting, the operator sits on the seat thus

having his weight supported almost entirely by the straight or flat portion of the runner, the rider by inclining his body backward or forward or sidewise steers the device in 5 a manner well understood by those by whom these devices are used. It will be noticed that there is ample room in front of the post for the rider, ordinarily a child, to swing his or her legs, thereby helping to maintain 10 balance and to steer the device. Another object of the space immediately in front of the post provided in my improved device is that the rider can grasp the seat with a hand on each end and holding the jumper in 15 a slanting position behind his back may run until he attains sufficient momentum and then bring the runner into contact with the snow so as to apply the momentum to the sled, thus facilitating the use of the device 20 in sliding even on level portions. It will also be noticed that the seat is inclined slightly backward and is, therefore, more comfortable especially when coasting down inclined surfaces.

25 In use the device is very readily steered by leaning to one side or the other so as to avoid obstructions and follow a curved course. The operator can also throw his weight backward to the extreme rear end 30 of the runner which presents a small bearing surface and facilitates turning even a sharp angle if necessary.

What I claim and desire to secure by Letters Patent is:

35 1. In a coasting sled the combination with a single runner, of a seat post comprising two vertically disposed standards having their ends separated and being bent inwardly toward and into contact with each 40 other, and a horizontally disposed top member connecting the upper ends of said standards, the lower ends of said standards being secured to the runner, and a seat supported upon said horizontally disposed member.

45 2. In a coasting sled the combination with a single runner, of a seat post comprising two vertically disposed standards, having their ends separated and having intermediate portions bent inwardly toward and into contact with each other, and a horizontally disposed member connecting the upper ends of said standards, the lower ends of said standards being secured to the runner, a 50 front brace connected to the runner forward of the seat post and having its upper end engaging one of said standards adjacent to said point of contact with the other standard, means connecting said standards and 55 the upper end of said brace together and a seat supported by the horizontally disposed member.

60 3. In a coasting sled the combination with a single runner, of a seat post comprising 65 two vertically disposed standards, having

their ends separated and having intermediate portions bent inwardly toward and into contact with each other, and a horizontally disposed member connecting the upper ends of said standards, the lower ends of 70 said standards being secured to the runner, a front brace connected to the runner forward of the seat post and having its lower end provided with a forwardly extending foot extending toward the front end of the 75 runner for reinforcing the same, and having its upper end engaging one of said standards, adjacent to its point of contact with the other standard, means for rigidly uniting the contacting portions of said standards and the upper end of said front brace, 80 and a seat supported on said horizontally disposed member.

4. In a coasting sled the combination with a single runner, of a seat post comprising 85 two vertically disposed standards having their ends separated and being bent inwardly toward and into contact with each other, and a horizontally disposed top member connecting the upper ends of said standards, the lower ends of said standards being secured to the runner, means for rigidly connecting the contacting portions of said standards, and a seat supported on the horizontally disposed member.

5. In a coasting sled the combination with a single runner, of a seat post comprising 95 two vertically disposed standards having their ends separated and being bent inwardly toward and into contact with each other, and a horizontally disposed top member connecting the upper ends of said standards, the lower ends of said standards being secured to the runner, detachable clamping members for engaging the opposite faces of 100 said standards adjacent to said contacting portions thereof, bolts connecting said clamping members, and a seat supported upon said horizontally disposed member.

6. In a coasting sled the combination with 110 a single runner, of a seat post comprising two vertically disposed standards, having their ends separated and having intermediate portions bent inwardly toward and into contact with each other, and a horizontally disposed member connecting the upper 115 ends of said standards, the lower ends of said standards being secured to the runner, a front brace connected to the runner forward of the seat post and having its upper end 120 engaging one of said standards adjacent to said point of contact with the other standard, a clamping member engaging one of said standards adjacent to its point of contact with the other, a clamping member engaging the other of said standards and the upper end of said front brace, bolts connecting said clamping members, and a seat supported by said horizontally disposed member.

ing longitudinally disposed flanges and a seat supported by said seat post and having grooved portions for engaging said flanges, said seat and said horizontally disposed

end portions being bent inwardly toward each other to form contacting knees, and the lower ends of said end portions being secured to the runner at points separated longitudinally thereof, and a seat supported on said horizontally disposed portion. 35

5 member being provided the one with projections engaging interlocking apertures in the other to prevent the longitudinal movement of said parts with respect to each other, and lateral braces having their upper ends connected to said seat and their lower ends connected to said seat post adjacent to the contacting portions thereof.

17. In a coasting sled the combination of

40

a single runner, having a substantially flat rear portion and an upwardly inclined portion extending forward thereof, a seat post supported on the flat portion of the runner, formed of a single piece of channel iron and comprising vertically disposed standards 45 bent inwardly to form contacting knees, and a horizontally disposed portion connecting the upper ends of the standards and having lateral flanges projecting upwardly, a front brace secured to the runner forward of the 50 seat post, the upper end of said brace extending to the knee portion of the adjacent standard, clamping members engaging said standards and front brace bolts connecting said clamping members, a seat provided 55 with grooves to receive the upwardly extending flanges of the horizontally disposed seat post member, pins secured to the seat and engaging apertures in said member, and lateral braces secured to the seat, and having 60 portions engaging said bolts between said clamping members.

15. In a coasting sled the combination with a single runner having its ends bent to

16 form loops, a seat post comprising vertically disposed portions separated at their upper and lower ends and bent inwardly into contact between their upper and lower ends, the lower ends being connected to the runner 20 and the upper ends being connected by a horizontally disposed seat supporting member, a seat and means for detachably connecting said seat to the seat post, whereby said seat may be removed and the loops of 25 the runner engaged with a rod at the front and rear ends thereof to facilitate packing for transportation.

16. In a coasting sled the combination with a single runner, of seat post formed of 30 a single piece of metal having its central portion disposed substantially horizontally and its end portions disposed vertically said

In testimony whereof I affix my signature.

THOMAS THEODORE HART.
